United States Patent Office

Des. 190,960
Patented July 25, 1961

190,960

CHAIN BLOCK

Kazuo Maeda, Fujisawa, Japan, assignor to Kabushiki
Kaisha Kito Seisakusho, Kawasaki, Japan

Filed May 25, 1960, Ser. No. 60,730

Term of patent 14 years

(Cl. D41—1)

FIG. 1 is a front elevational view of a chain block, showing my new design;

FIG. 2 is a rear elevational view thereof;

FIG. 3 is a top plan view thereof;

FIG. 4 is a bottom plan view thereof;

FIG. 5 is a right side elevational view thereof; and

FIG. 6 is a left side elevational view thereof.

I claim:

The ornamental design for a chain block, as shown.
